APPARATUS FOR MIXING CONCRETE AND
THE LIKECharles F. Ball, Wauwatosa, Wis., assignor to
Chain Belt Company, Milwaukee, Wis., a cor-
poration of Wisconsin

Application December 1, 1936, Serial No. 113,691

4 Claims. (Cl. 83—73)

The invention relates to apparatus for mixing or agitating concrete and the like, and more particularly to a modified form of closure operating mechanism for the multiple compartment mixing receptacles of the type described and claimed in my prior co-pending application filed September 9, 1936, Serial No. 100,008. It has for its principal object the provision of operating mechanism for the transfer door of such receptacles, which will in no wise interfere with the passage of the concrete making materials through the charging chute into the preliminary mixing compartment, whereby such charging will be facilitated.

With the above and other objects in view, which will appear as the description proceeds, the invention consists in the novel details of construction, and combinations and arrangements of parts, more fully hereinafter described and particularly pointed out in the appended claims.

Referring to the accompanying drawings forming a part of this specification in which like reference characters designate like parts in all the views:—

Figure 1 is a vertical longitudinal sectional view of a multiple compartment mixing receptacle of the type disclosed in my said prior application, equipped with transfer-door operating mechanism constructed and arranged in accordance with my present invention;

Fig. 2 is an end elevational view of the parts shown in Fig. 1, as seen from the left of said figure; and

Fig. 3 is an enlarged horizontal sectional-plan view, taken approximately on the plane indicated by the line 3—3 of Fig. 1, looking down.

As in my said prior application, the multiple compartment mixing receptacle may comprise a tubular shell 10, the open ends of which are closed by the heads 11 and 12, provided respectively with the charging and discharging openings 13 and 14, the former of which has associated with it a charging hopper or chute 15 for receiving and passing the concrete making materials into the drum, while the latter may have associated with it any suitable form of discharge chute or mechanism, not shown. The shell 10 is also provided with an intermediate transverse partition 16, dividing its interior into primary and secondary mixing compartments 17 and 18, and communication between which is afforded by a transfer opening 19 in the said partition 16, which opening is preferably surrounded by an angle member 20, serving not only to reinforce the partition wall but also as a seat

for the transfer controlling door or closure 21. The primary mixing chamber 17 is provided with a coniform deflecting member 22 extending from the shell 10 to the opening 19, and said chamber is further provided with a plurality of mixing or agitating blades 23 and transfer blades or troughs 24, only some of each of which are here illustrated. The compartment 18 is in like manner provided with mixing blades 25 and pick-up or discharge buckets 26, only some of which also are illustrated. The drum is provided with the usual tracks 27, and sprocket or other equivalent power transmitting element 28 by means of which it may be driven.

The transfer door 21 is connected by a flexible connection 30 to one end of its operating shaft 31 which extends axially of the chamber 17 and is splined in a support 32 rigidly mounted within the chamber as upon the transfer troughs 24. The shaft 31, instead of extending through the charging hopper 15 as in my said prior application, terminates short of the charging opening 13, and has journaled upon its end a transversely extending yoke 33, to the outer ends of which are rigidly secured the horizontally extending arms 34 which project through the charging opening 13 outside of the hopper 15. The outer ends of the said arms 34 are pivotally connected as at 35 to rock arms 36 carried by a rock shaft 37, which may be actuated from an automatic power operated control mechanism 38 through a pitman 39 embodying an overload relief construction, and a lever 40, as in said prior application.

As best shown in Fig. 3, the yoke 33 is provided with a hub 41, which receives the end of shaft 31. A pair of anti-friction bearings 42 and 43 are mounted upon the said shaft end and maintained in spaced relation by the spacing members 44 and 45. The bearing 42 abuts against a shoulder 46 within the hub, while the inner end of a threaded cap 47 bears against the bearing 43. The shaft and bearings are thus restrained against longitudinal movement within the hub, so that reciprocations of the yoke, imparted to it by the arms 34 and 36, will be positively transmitted to the shaft 31, whereby the transfer door 21 may be opened and closed, the said shaft being at the same time free to rotate with the door. A suitable seal 48 may be provided within cap 47 to prevent the abrasive concrete mixture from working its way into the bearings 42 and 43.

It will be readily apparent from the foregoing that the present invention provides a construc-

tion whereby the transfer door may be positively actuated as in my prior application Serial No. 100,008, while because of the yoke and spaced arm arrangement, charging of the concrete materials into the mixing drum may take place without interference such as might be caused by the door operating shaft passing through the charging chute or hopper.

It is obvious that those skilled in the art may 10 vary the details of construction as well as the precise arrangement of parts without departing from the spirit of the invention, and therefore it is not wished to be limited to the above disclosure except as may be required by the claims.

15 What is claimed is:—

1. In apparatus for mixing concrete and the like, a rotatable receptacle having oppositely disposed charging and discharging openings; a fixed charging chute extending through said charging opening and having its side walls spaced from the walls of said opening; a reciprocable closure for said discharging opening; a shaft for moving said closure, mounted within said receptacle for rotation therewith and for reciprocating movements relative thereto; means for reciprocating said shaft including a member having elements extending from within to without said receptacle through the space between the side walls of the chute and the walls of the opening; and a connection between said member and shaft arranged to impart reciprocating movements to said shaft while permitting of relative rotation thereof.

2. In apparatus for mixing concrete and the like, a rotatable receptacle having oppositely disposed openings for ingress and egress of the material; means for directing material through one of said openings; a movable closure for the other of said openings; a shaft in said receptacle mounted for rotation therewith and for axial movements relative thereto, said shaft being connected at one end to said closure and at its other end terminating short of said material direct-

ing means; a yoke within said receptacle journaling the last named end of said shaft and arranged to impart said axial movements to the latter, said yoke having arms extending exteriorly of said material directing means to the outside of said receptacle; and means for reciprocating said arms.

3. In apparatus for mixing concrete and the like, a rotatable receptacle having oppositely disposed openings for ingress and egress of the material; a fixed chute for feeding material through said ingress opening; a reciprocable closure for said egress opening; a shaft for moving said closure, mounted within said receptacle for rotation therewith and for reciprocating movements relative thereto, said shaft terminating short of said ingress opening; a yoke having a hub receiving the end of said shaft; anti-friction bearings between said shaft and hub; spaced arms rigid with said yoke, extending through said ingress opening to either side of said chute; and means for reciprocating said arms.

4. In apparatus for mixing concrete and the like, a rotatable receptacle having oppositely disposed openings for ingress and egress of the material; a fixed chute for feeding material through said ingress opening; a reciprocable closure for said egress opening; a shaft for moving said closure, mounted within said receptacle for rotation therewith and for reciprocating movements relative thereto, said shaft terminating short of said ingress opening; a non-rotatable yoke having a hub receiving the end of said shaft; anti-friction bearings between said shaft and hub; means for preventing axial movements of said shaft relative to said hub; spaced arms rigid with said yoke, extending through said ingress opening to either side of said chute; and means for reciprocating said arms.

CHARLES F. BALL.
